(57) **CLAIM**

The ornamental design for a rolling pin as shown and described.

DESCRIPTION

FIG. 1 is an isometric view of the rolling pin.

FIG. 2 is a front view of the rolling pin of FIG. 1.

FIG. 3 is a rear view of the rolling pin of FIG. 1.

FIG. 4 is a right side view of the rolling pin of FIG. 1.

FIG. 5 is a left side view of the rolling pin of FIG. 1.

FIG. 6 is a top view of the rolling pin of FIG. 1; and,

FIG. 7 is a bottom view of the rolling pin of FIG. 1.

The broken lines show portions of the rolling pin which form no part of the claimed design.

1 Claim, 6 Drawing Sheets
